UNITED STATES PATENT OFFICE.

WALTER HAWTHORN AND THOMAS FORSYTH WATSON, OF WOODFORD,
ENGLAND.

DESIGN FOR A HAIR-PIN.

SPECIFICATION forming part of Design No. 25,407, dated April 21, 1896.

Application filed February 24, 1896. Serial No. 580,523. Term of patent 3½ years.

To all whom it may concern:

Be it known that we, WALTER HAWTHORN and THOMAS FORSYTH WATSON, subjects of the Queen of Great Britain and residents of 5 Woodford, in the county of Essex, England, have invented a new Design for Hair-Pins, of which the following is a full, clear, and exact specification thereof.

This invention relates to a new and original 10 design for hair-pins, of which the following is a specification, reference being had to the accompanying drawing, showing a part thereof.

The figure is a view of a hair-pin, showing the design.

The leading feature of our design consists 15 in the bent portion *b* of the prongs *a* of the hair-pin forming the head of the pin.

What we claim is—

The design for a hair-pin herein shown and described having a bent end *b* as shown. 20

In testimony that we claim the foregoing we have hereunto set our hands this 13th day of January, 1896.

WALTER HAWTHORN,
THOMAS FORSYTH WATSON.

Witnesses:

JAMES FLEMING,
PLION BUNDY.
